[57] ABSTRACT

A cigarette filler rod forming apparatus includes an

4 Claims, 3 Drawing Figures

FIG. 1

FIG. 2

TOBACCO MANIPULATING MACHINES

FIELD OF INVENTION

The present invention is directed to tobacco manipulating machines.

BACKGROUND TO THE INVENTION

A long known difficulty in the cigarette making art has been the irregularity in the formation of a filler rod which is caused by showering tobacco by gravity onto a travelling surface in such a way that tobacco already on the surface is actually moving past the falling tobacco. That condition results in irregularities because any upstanding or projecting parts of the filler or stream, such as is caused by the deposition of lumps of tobacco in the stream, tend to intercept falling tobacco particles, thus causing undue accumulation of tobacco in front of and on top of such projecting parts, with corresponding sparsity of tobacco immediately behind such parts. This result may be termed the "peak and valley" or "shadow" effect.

The resultant filler rod has a complete lack of uniformity of quantity of tobacco in the cross section thereof along its length, which produces cigarettes of nonuniform quality, which is unacceptable.

One prior art suggestion is overcome or at least minimize the problem appears in U.S. Pat. No. 3,030,965. In this patent, a tobacco filler rod is formed on a perforated conveyor band moving longitudinally thereof by means of a stream of air flowing at high velocity through a passage towards and through the conveyor band so as to carry tobacco particles through the passage in substantially separated form and to deposit the tobacco particles on the conveyor band. In this prior art structure, the high velocity air stream is wholly confined laterally by the passage, and all the air which flows through the passage leaves the passage by flowing through the perforated conveyor band and through the tobacco on the conveyor band.

Thus, most of the tobacco particles reaching the conveyor band do so in the form of separate particles and lumps of tobacco are substantially absent from the stream. The tobacco filler rod built up on the conveyor band by the arrival of these substantially separated particles is subjected to the minimum disturbance during its formation, since an individual particle has insufficient mass to create any significant disturbance or displacement of tobacco already on the conveyor band.

In addition, in the preferred operation of the apparatus of U.S. Pat. No. 3,030,965, the tobacco particles which on reaching the conveyor band are moving up with substantially the speed of the air which carries them less the reduction in speed due to gravity, reach the conveyor band or the partly-formed filler rod carried thereby with substantially no movement relatively to the conveyor band considered in the direction of movement of the band. Thus, the effect is the same as if the conveyor band were stationary and the tobacco particles travelled to it in directions substantially normal to the band. In this way, the "peak-and-valley" or "shadow" effect of the prior art technique is sought to be overcome and some improvement in the uniformity of weight of tobacco along the length of the filler rod has been experienced.

However, the formation of filler rods using the apparatus of U.S. Pat. No. 3,030,965 produces filler rods which exhibit other defects. Due to the high velocity of

impact of the individual tobacco particles on the partly-formed filler rod on the conveyor band and the porosity of the surface of the partly-formed rod, there is a tendency for some of the tobacco particles to be buried in the partly-formed rod rather than lying on the surface of the partly-formed filler rod. Smaller tobacco particles have greater penetrative power than longer tobacco particles and the filler rod tends, therefore, to have a classification of tobacco particles sizes in its cross-section.

This "classification" effect leads to problems in later handling of the filler rod during the formation of cigarettes therefrom since the portion of the cross-section containing the higher proportion of small particles has a greater tendency to be detached from the ends of cigarettes than the portion of the cross-section containing the higher proportion of longer particles. The irregular fall-out of quantities of tobacco from the ends of cigarettes is clearly undesirable and should be avoided, if possible. In addition, to producing bad cigarette ends, the classification effect also may lead to uneven burning rates for the cigarette when smoked.

Another problem encountered by filler rods produced in the apparatus of U.S. Pat. No. 3,030,965 due to the high rate of impacting of tobacco particles together at the conveyor band is a limitation on the "filling power" of the filler rods. The "filling power" of a filler rod is its ability to fill a paper cigarette tube. It is measured by determining the weight of tobacco required to produce a particular hardness of cigarette. The less tobacco necessary to provide the predetermined hardness of cigarette the greater is the filling power of the tobacco filler rod from which the cigarette is formed.

Consumer acceptance of cigarettes is based more on the feel of a cigarette, i.e., its hardness, than on the absolute tobacco content of the cigarette. Thus, where a predetermined hardness of cigarette is desired, and that hardness is provided by less tobacco, i.e. from a filler rod of greater filling power, then manufacturing economies can be effected.

A further difficulty arises in the practical operation of the apparatus of U.S. Pat. No. 3,030,965. The velocity with which the air can be cause to flow up the passage and hence the speed of formation of tobacco filler rod, is limited by the resistance offered to the air flow by the tobacco on the conveyor band and the resistance of the band itself. This problem has led to the positioning of openings in the side walls of the passage in the region of the conveyor band so that part of the air can escape from the passage and be separated from the tobacco while the latter continues to move towards the conveyor band with the remainder of the air. This structure is described in U.S. Pat. No. 3,019,793.

The side wall openings while improving the speed of operation also introduce other problems. The openings generally are provided in the form of guide elements or louvres which are inclined to the passage so as to guide air out of the passage in a rearward direction considered in the direction in which air moves through the passage. Operation of rod-forming machines having this structure has shown these machines to be sensitive to the air supply, the angle of inclination of the louvres and to normal operational variations. Unless these factors are properly balanced within very narrow tolerances, some loss of tobacco through the louvres and/or jamming of the passage by tobacco may occur. The

sensitivity in due to the necessity to achieve a clear separation of a considerable portion of the air passing through the passage into and through the louvers without affecting the path of movement of tobacco to the conveyor band. This arrangement, further is incapable of affecting the classification and filling power problems of the product from the apparatus of U.S. Pat. No. 3,030,965.

An additional operating problem of the apparatus of U.S. Pat. No. 3,030,965 is described in U.S. Pat. No. 3,091,244. There is tendency for air to be drawn by suction from atmosphere through the gap between the filler rod and the end wall of the passage so as to enter the passage. The air which thus passes through the gap moves lengthwise of the filler rod against the direction of endwise movement of the filler rod and this is found to have a disturbing effect on the formation of the filler rod by displacing tobacco lengthwise of the filler rod, thereby introducing some lack of uniformity to quantity of tobacco in the filler rod. In order to attempt to overcome this problem, as described in U.S. Pat. No. 3,091,244, closure means is located adjacent the end wall of the passage past which the conveyor carries the filler rod formed thereon in the passage. The closure means includes a part which engages the filler rod while closing the gap between the end wall and the filler rod and is flexible to accommodate variation in depth of the filler rod.

Many different structures of closure means have been used on cigarette-making machines constructed in accordance with the principles of U.S. Pat. No. 3,030,965 and none has been found to be wholly satisfactory.

It will be apparent therefore that the prior art filler rod-forming apparatus of the type described in U.S. Pat. Nos. 3,030,965 and 3,019,793 suffers from drawbacks which limit the quantity of the cigarette product and the economics of the cigarette making operation, and which render operation a precise and delicate matter.

SUMMARY OF INVENTION

In accordance with the present invention, a cigarette filler rod-forming apparatus constructed in accordance with the principles of U.S. Pat. No. 3,030,965, is modified by positioning a tobacco gathering means in the passage adjacent the air-permeable and tobacco-impermeable foraminous conveyor band. The walls defining the passage are substantially continuous and no openings or louvres are provided for the removal of air, other than those required for removal of air through the gathering means.

The tobacco gathering means used in the present invention comprises a plurality of shallow cylindrical discs having their axes intersecting the side walls of the passage approximately at right angles thereto. Each disc has substantially the same diameter and has a peripheral wall extending between the side walls and including an air-permeable, tobacco-impermeable foraminous surface. Each disc is hollow and vacuum is applied internally so that suction is applied through the foraminous surfaces.

The foraminous surfaces each may be rotated about its axis of the disc at substantially the same speed in the same direction. Vacuum interrupting means is positioned to prevent the application of suction through a

selected arcuate length of each of the foraminous surfaces.

BRIEF DESCRIPTION OF DRAWINGS

FIG. 1 is a schematic part sectional view of one embodiment of the invention;

FIG. 2 is a sectional view taken on line 2-2 of FIG. 1; and

FIG. 3 is an elevational part sectional view of a detail 10 of a gatherer for use in the embodiment of FIG. 1.

DESCRIPTION OF PREFERRED EMBODIMENTS

Referring to the drawings, a tobacco filler rod forming apparatus 10 includes a narrow passage 12 formed by side walls 14 and 16 and end walls 18 and 20 extending continuously from one end of the passage to the other. At the top of the passage 12 an endless metal conveyor band 22 provided with perforations which are air permeable but tobacco impermeable passes over 20 pulleys 24 and 26 with suitable adjustment being provided to take up slackness in the band.

The band 22 extends directly beneath a suction chamber 28, the edges of the band 22 engaging shoulders formed on opposing members 30 which form a conduit 32 leading to the suction chamber 28. This construction also is illustrated in U.S. Pat. No. 3,030,965.

In accordance with the present invention, the louvres illustrated in U.S. Pat. No. 3,019,793 and the closure means required in U.S. Pat. No. 3,091,244 are omitted 30 and a tobacco gatherer 34 is positioned in the passage 12 in any convenient manner between the upwardly-flowing stream of air and tobacco and the conveyor band 22.

The gatherer 34 comprises a plurality of shallow, hollow, cylindrical discs 36 extending substantially across the width of passage 12 and shown in more detail in FIGS. 2 and 3. Each disc 36 has a peripheral wall 38 with a continuous air-permeable tobacco impermeable foraminous surface 40 therein. Each of the surfaces 40 is mounted for rotation about the axis of the disc 36 by means not shown and has substantially the same diameter.

Vacuum is applied internally of each of the discs 36 in any convenient manner, not shown, whereby suction is applied through the foraminous surfaces 40. Openings usually are necessary in the side walls 14 and 16 to allow the application of vacuum. However, such openings clearly contrast with the openings described in U.S. Pat. No. 3,019,793 wherein the air is removed 50 before the tobacco particles reach the conveyor. A vacuum interrupting shoe 42 is positioned internally of each disc 36 to prevent the application of suction through an arcuate length of the foraminous surface 40 which does not include the tobacco particles intercepting portion thereof. Preferably the shoe 42 extends from the approximate point of nearest approach of the foraminous surface 40 to the conveyor band 22 90° in the direction of intended motion of the surface 40.

In addition as shown in FIG. 3, the straight line joining the axes 44 of the discs 36 preferably is inclined with respect to the conveyor band 22 for reasons discussed below in connection with the operation of the device.

The number of such discs 36 which may be used in the gatherer 34 may vary widely although about 6 to 8 are most useful. Usually, all the foraminous surfaces 40 are continuous, although it is possible to utilize one of

the wheels 36 to provide dense ends in the cigarettes, if desired, by providing one of the peripheral walls 38 with accurately spaced-apart air-permeable portions only.

OPERATION

In operation, a high speed moving stream 46 of air and substantially spaced apart tobacco particles, is drawn upwardly through the passage 12 by the action of the suction internally of the surfaces 40 and into contact with the portion of the foraminous surface 40 of the rotating discs 36 intercepting the stream 46 and designated a substream forming surface. The tobacco particles may be fed into the stream 46 in any convenient manner, such as is described more fully in U.S. Pat. No. 3,030,965. The quantity of tobacco in the stream 46 usually is substantially uniform across the width thereof. The tobacco particles are fed to the inlet of the passage 12 in substantially separated form in any convenient manner, for example, as described in U.S. Pat. No. 3,030,965.

Under influence of the suction applied through the surface 40 of each disc 36, the tobacco particles in the moving stream in the passage 12 are gathered on the substream forming surface portion of the foraminous surfaces 40 to provide a narrow substream of tobacco 48 on each of the surfaces 40. A "substream" of tobacco, as used herein, is intended to refer to an elongated narrow stream of tobacco particles which itself is incapable of use as a filler rod to form cigarettes but which may be joined with other like streams to form a filler rod from which cigarettes may be formed.

The substreams 48 all usually contain the same quantity of tobacco. The depth of the substream 48 increases in its direction of motion, as illustrated, until the foraminous surface 40 conveys the substream under the influence of the suction out of contact with the stream 46.

The substreams 48 have only a shallow depth and hence the classification of particle sizes discussed above in connection with the products of the apparatus of U.S. Pat. Nos. 3,030,965 and 3,019,793 is minimized or eliminated entirely. Further, since the surface 40 on which the substream 48 is formed is arcuate, then the combined length of tobacco receiving surface provided by the plurality of discs 36 is $\pi/2$ times the length of the conveyor band 22 in the path of the stream 46. This results in greater air-permeable surface area through which to pass the air.

Since the substreams 48 are shallow, each individual particle of tobacco in the substream 48 is substantially completely under the influence of the suction applied through the surface 40. The shallow depth of the substreams 48 allows all the air in the stream 46 to be handled readily by the suction across the surface 40 since the substream 48 offers little or no resistance to the air flow. This latter result is in contrast to the structure disclosed in U.S. Pat. No. 3,030,965 wherein problems of air handling due to resistance of the filler rod on the conveyor band restricted the speed of operation and lead to the louvre modification of U.S. Pat. No. 3,019,793. The speed of operation of the apparatus of the present invention is not restricted in the manner of the prior art.

It will be observed that while, in the present invention, the same quantity of tobacco is formed into a filler rod as is the case using the prior art apparatus of U.S.

Pat. No. 3,030,965, the quantity of tobacco in the present invention which is formed into the filler rod, first, is evenly distributed across the width of the stream 46 by way of the substreams 48 and, second, is distributed over a longer surface length due to the arcuate nature of the discs 36. Therefore, the apparatus of the present invention is able to handle any desired volume of air in the passage 12 commensurate with the desired speed of formation of the filler rod. Hence, the necessity to use the louvre modification of U.S. Pat. No. 3,019,793, with its attendant operational problems, as discussed above, is avoided. The structure provided by the present invention, therefore, overcomes the air handling problems of the structure of U.S. Pat. No. 3,030,965 while avoiding the operational problems of the louvre modification of U.S. Pat. No. 3,019,793.

Each substream 48, after formation thereof, is conveyed under the influence of the suction through the surface 40 to a point wherein the tobacco particles in the substream are moving adjacent to and in substantially the same direction as the conveyor band 22 or a partly-formed tobacco filler rod 50 already deposited on the conveyor band 22.

The discs 36 are rotated at substantially the same speed as the linear speed of the band 22 and hence the tobacco particles in the substream 48 have substantially the same speed as the band 22 and the partly-formed filler rod 50 on the band.

Suction is applied through the band 22 by means of the suction chamber 28 to hold the partly-formed filler rod 50 to the band 22.

When the tobacco particles in the substream 48 are moving adjacent to, substantially the same direction as and substantially the same speed as the band 22, the suction applied through the surface 40 is released by the action of the vacuum shoe 42 at which point the tobacco particles become under the influence of the suction applied through the band 22 and hence the particles of the substream 48 are laid on the band 22 where

the right-most disc 36 (as viewed in FIG. 1) is considered or on the partly-formed rod 50 when the remaining discs are considered. The procedure occurs at each disc 36 and hence the filler rod is built up to its final thickness across the width of the passage 12 and a tobacco filler rod 52 is removed from the passage 12 in engagement with the band 22. The tobacco filler rod 52 is passed to further processing to form cigarettes in the well-known manner, as described fully in U.S. Pat. Nos. 3,019,793 and 3,030,965.

The substreams 48 therefore, in effect, are laid up on each other to form the filler rod 52, while the tobacco particles on the surface of the conveyor band 22 retain substantially the same juxtaposition as existed in the substreams 48.

As illustrated in FIG. 3, as a result of the inclination of the line joining the axes 44 to the band 22 in accordance with the preferred embodiment, the substream 48 when positioned on the band 22 or on the partly-formed rod 50 is substantially tangential to the surface 40 which assists in the gentle laying up of the substream 48 to form the filler rod 52 at the point of discharge. This arrangement and manner of operation is preferred although others may be used provided that, when the tobacco particles are positioned on the band 22 or on the partly-formed filler rod 50, they have substantially the same juxtaposition as existed in the substream 48.

Therefore, the substantially separated tobacco particles in the stream 46 are captured by the use of suction, conveyed under the influence of suction as a substream of tobacco to a discharge point where they are transferred intactly to the influence of the suction applied through the conveyor band 22. Since there is little or no relative speed between the band 22 and the tobacco particles in the substreams 48, the quantity of tobacco along the filler rod 52 is substantially uniform and, in this respect, the filler rod provided by the present invention is at least as good as that provided by the apparatus of U.S. Pat. No. 3,030,965.

Since the tobacco particles are completely under the influence of vacuum from their initial capture on the surfaces 40 to their positioning on the conveyor band 22, any air drawn by suction through the gap between the filler rod and the end wall 18 of the passage 12 has substantially no effect on the filler rod and hence the closure means of U.S. Pat. No. 3,091,244 may be omitted and its attendant problems avoided.

In addition, since the substreams 48 are thin, little or no classification of tobacco particles occurs and hence the filler rod 52 has a substantially uniform distribution of particle size in the cross-section thereof. This is in complete contrast to the filler rod produced by the rod-forming apparatus of U.S. Pat. Nos. 3,030,965 and 3,019,793 wherein classification occurred. Therefore, the apparatus of the present invention produces a filler rod which is superior to that produced by the prior art machines and which does not have bad ends.

Further, since the filler rod 52 is formed by the apparatus of the present invention by the laying up of a succession of layers of tobacco across the width of the passage 12 and there is substantially no disturbance of the interface between the layers during the laying up, the filler rod 52 has excellent filling power which is superior to that of tobacco filler rods formed on the rod-making apparatus of U.S. Pat. Nos. 3,030,965 and 3,019,793 leading to a more economic tobacco use for the same cigarette hardness.

SUMMARY

The filler rod-forming machine of the present invention therefore has several advantages over the prior art, in that:

1. The machine is capable of operating at any desired rod forming speed without encountering (a) the limitations of U.S. Pat. No. 3,030,965 caused by resistance of the partly-formed rod to air flow (b) the operational problems of the air flow separation technique of U.S. Pat. No. 3,019,793, and (c) the operational problems of the closure means of U.S. Pat. No. 3,091,244.

2. The machine forms a filler rod having a substantially uniform distribution of particle sizes in its cross-section, resulting in uniformly good cigarette ends and uniform burning rates, in contrast to filler rods produced on the rod-making machines of U.S. Pat. Nos. 3,030,965 and 3,019,793 which suffer from classification problems;

3. The machine forms a filler rod having a filling power superior to filler rods produced by the rod-making machines of U.S. Pat. Nos. 3,030,965 and 3,019,793; and

4. The machine exhibits the above advantages without otherwise harming the uniformity of the quantity of tobacco in the length of the filler rod which is at least substantially as good as that of filler rods produced by

the rod-making machines of U.S. Pat. Nos. 3,030,965 and 3,019,793.

Modifications are possible within the scope of the invention.

What we claim is:

1. A continuous tobacco filler rod-making apparatus comprising continuous opposed side and end walls defining an enclosed relatively thin and flat elongated passage having an inlet opening at a lower longitudinal extremity thereof, and having a tobacco gathering means closing the upper longitudinal extremity thereof, means to feed tobacco in the form of substantially separated particles into the inlet opening, said tobacco gathering means comprising a plurality of shallow cylindrical discs mounted to collect and convey a plurality of tobacco substreams and having their axes intersecting said opposed side walls approximately at right angles thereto,

each of said discs having substantially the same diameter and having a peripheral wall extending between said opposed side walls, each said peripheral wall including an air-permeable tobacco-impermeable foraminous surface rotated about said axis at substantially the same speed in the same direction,

each of said discs being hollow and the interior thereof having a pressure that is less than atmospheric exerted through said foraminous surface to cause air to move continuously through said passage as a high velocity stream flowing from the inlet towards said gathering means and to convey said tobacco particles fed to the inlet in said air stream in said substantially separated form from the inlet towards said gathering means,

the portion of said foraminous surface of each of said discs intercepting the tobacco particles borne by said high velocity air stream constituting a narrow substream forming surface, vacuum interrupting means positioned internally of each of said discs to prevent the application of said pressure over a selected arcuate length of each foraminous surface excluding substantially completely said substream forming surface to release tobacco particles of said substreams from said foraminous surface,

a narrow air-permeable and tobacco-impermeable foraminous conveyor arranged to move lengthwise adjacent said discs outside said passage to receive the tobacco particles of said plurality of tobacco substreams from said gathering means when said particles are released to form on said conveyor a filler rod, and

means to hold tobacco to said conveyor, said latter means including a suction device arranged to draw air through said conveyor to exert pressure on tobacco on said conveyor to hold the tobacco against the conveyor,

said vacuum interrupting means being positioned relative to each said foraminous surface to extend over said selected arcuate length thereof from approximately the point of closest approach of said surface to said conveyor, to release the tobacco particles of said substreams at said approximate point of nearest approach,

said conveyor being substantially flat and a straight line joining said axes being inclined with respect to said conveyor such that the substreams received

from each of said discs onto the conveyor is substantially tangential to said foraminous surface and to the under surface of the conveyor or the rod being formed thereon.

2. The apparatus of claim 1 wherein each of said foraminous surfaces is circumferentially continuous.

3. The apparatus of claim 1 wherein one of said plurality of discs is provided with a peripheral wall having arcuately spaced-apart air permeable portions consti-

tuting said foraminous surface and the remainder of said plurality of discs is provided with a substantially circumferentially continuous foraminous surface in the peripheral wall thereof.

5. 4. The apparatus of claim 1 wherein said vacuum interrupting means extends through 90° of the arcuate length of said foraminous surface.
